UNITED STATES PATENT OFFICE.

GEORGE W. PIGOTT, CHARLES P. PIGOTT, REUBEN H. PIGOTT, AND LEEMAN L. SHINN,
OF WEST UNION, WEST VIRGINIA.

WRENCH.

Application filed March 24, 1924. Serial No. 701,572.

To all whom it may concern:

Be it known that we, GEORGE W. PIGOTT, CHARLES P. PIGOTT, REUBEN H. PIGOTT, and LEEMAN L. SHINN, citizens of the United States, residing at West Union, in the county of Doddridge and State of West Virginia, have invented certain new and useful Improvements in a Wrench, of which the following is a specification, reference 10 being had therein to the accompanying drawings.

This invention relates to a wrench, and the object of the invention is the construction of a simple and efficient wrench formed, 15 preferably, in one piece, and including elements whereby nuts of different size can be easily clamped and screwed upon or unscrewed off bolts, and the like.

With the foregoing and other objects in view, our invention comprises certain novel combinations, constructions and arrangements of parts as will be hereinafter described, illustrated in the accompanying drawings, and more particularly pointed 25 out in the appended claim.

In the drawing:

Figure 1 represents a view in elevation of a wrench constructed in accordance with the present invention.

Figure 2 is a fragmentary perspective view of the wrench.

Referring to the drawings by numerals, 1 is the handle, upon one side and one edge of which is formed a scale 2, which "scale" 35 is very useful as affording a rule for measurement, by the user of the wrench.

Integral with the handle 1 is a head 3, and integral with head 3 is a primary jaw 4 and an auxiliary jaw 5. These jaws are 40 provided with a concave, inner surface 6, against which nuts bear, when the wrench is in operation.

On the outer end of primary jaw 4 is formed right-angled portion 7, and on the 45 outer end of portion 7, and extending slightly inwardly is a cam portion 8. Cam portion 8 is serrated or toothed on its outer face for more efficiently engaging nuts 9 and 10 (dotted lines).

It will, therefore, be seen that we have 50 provided a wrench with an auxiliary jaw that is of a slightly curved structure where-

as the primary jaw is provided with an inwardly-extending portion terminating in a cam for engaging and clamping the nuts 55 when it is desired to screw a nut upon, or unscrew the same from a bolt.

It is to be noted that the inner face 11 of the portion 7 is straight and flat so that it constitutes one of three surfaces that will 60 snugly bind against nut 10, whereby the nut is efficiently held for operation. The three surfaces are the concave surface 6, the toothed surface of cam portion 8 and the straight surface 11. However, the nut 10 65 can be easily removed from the wrench by reversing the movement; that is, by unscrewing the nut, as the unscrewing action lessens the "clamping" pressure on the nut within the "socket," constituted by the several surfaces just specified.

While we have described the preferred embodiment of our invention, and have illustrated the same in the accompanying drawing, certain minor changes or alterations 75 may appear to one skilled in the art to which this invention relates, during the extensive manufacture of the same and we, therefore, reserve the right to make such alterations or changes as shall fairly fall 80 within the scope of the appended claim.

What we claim is:

As a new article of manufacture, a wrench comprising a handle provided with a substantially U-shaped head integral at its center with and extending across the outer end of said handle, a primary and an auxiliary jaw extending outwardly from said head parallel with the longitudinal axes of the handle, said primary jaw provided with a straight portion at right angles to said jaw and handle, said straight portion provided with a straight, flat nut-engaging inner face for snugly receiving an entire side of a nut, and a cam portion at the outer end of said 90 straight portion, substantially as shown and described.

In testimony whereof we hereunto affix our signatures.

GEORGE W. PIGOTT.
CHARLES P. PIGOTT.
REUBEN H. PIGOTT.
LEEMAN L. SHINN.
